UNITED STATES PATENT OFFICE

2,209,160

HEALTH AND BODY DEVELOPING MACHINE

Louis Greenberg, Chicago, Ill.

Substituted for abandoned application Serial No. 684,329, August 9, 1933. This application June 4, 1937, Serial No. 146,432

11 Claims. (Cl. 128—25)

The invention relates to a novel mechanical movement and particularly to a health and body developing machine, which forms the subject matter of my original application, Serial No. 5 684,329, filed August 9, 1933, of which the present application is a substitute.

It is an object of the invention to provide a compact and simple machine adapted to act directly on the legs and abdominal muscles of a 10 person, and indirectly, on the entire body of a person, in the nature of a massage.

A further object aims at providing a standing platform for a person, which platform is actuated to execute a universal tilting motion 15 whereby the person standing thereon is subjected to the influence of such motion and improves his muscular tone and health in general.

Another object aims at providing a universally tilting platform so that a person standing thereon experiences the reactions set up by the platform against the weight of the body.

A still further object aims at providing the machine with handle bars, enabling a person to hold the same so as to permit the body to receive 25 the full benefit of the action of the platform.

It is also an object to provide certain features of construction and arrangement tending to enhance the usefulness and efficacy of a machine of this character.

With these and other equally important objects in view, which will become apparent from a perusal of the invention, the latter comprises the means described in the following specification, particularly pointed out in the claims forming a 35 part thereof, and illustrated in the accompanying drawings, in which:

Fig. 1 is a front elevation of my invention.

Fig. 2 is a plan view.

Fig. 3 is a section on the line 3—3 of Fig. 2, 40 and

Fig. 4 is a section on the line 4—4 of Fig. 3, with parts in different positions.

Like parts are indicated by like symbols throughout the specification and drawings.

Referring to the drawings, the reference character 10 indicates generally a base or support which includes a front portion 11, and rear portions 12, serving as supporting legs, the legs being inter-connected by a horizontal web 13.

On the underside of web 13 is formed integrally a gear box 14, having a removable bottom plate 31, while on the upper face is an upwardly projecting supporting member 15. Mounted up- 50 on the base 10 is a motor 16 having a vertical

shaft 17 which extends downwardly into box 14 where is secured a driving pinion 18.

Pinion 18 is in mesh with a gear train which includes the gears and pinions 19 and 20 mounted on a stub shaft 25, gears 21 and 22 on a stub shaft 26, and gears and pinion 23 and 24, respectively, on a stub shaft 27.

The pinion 24 is in mesh with a gear 28 secured to a driven shaft 29 in a hub bearing 30 in the web 13.

The shaft 29 is positioned midway between the supports 11 and 15. The bottom plate 31 of the gear box 14 is secured by screws 32 and has bearings for the lower ends of the stub shafts 25, 26, 27 and the driven shaft 29, the upper ends of those elements seating in bearings in the web 13. The upper end of shaft 29 is provided with an enlarged head 33 having an upwardly directed inclined face 34 (Fig. 4) from which upstands an off-center pin 35 at right angles thereto.

The pin may be constructed integrally with the head 33. The point of connection of the pin 35 with the head or collar 33 is off center with respect to the axis of shaft 29, but the axis of the pin 35 intersects the axis of shaft 29.

Pivoted upon the spaced supporting members 11 and 15, as by pivot pins 36, is a rigid frame member generally designated by 37, which may include front and rear walls 38 and 39 connected by side members 40, as illustrated in Figs. 2 30 and 3.

The walls 38 and 39 are formed with concave inner faces, as shown at 41. A rigid plate or platform 42, herein shown as being square, of sufficient size to conveniently support the two feet 35 of a user, and conforming to the interior dimensions and contours of frame 37, is pivoted to the frame member 37 upon an axis at right angles to the axis of the pins 36 by the bearing pins 43 carried in the side members 40. The platform is provided with a low encircling side wall or flange 44 and with a centrally located boss 45 apertured as at 46 to receive and form a bearing for the upper end of the pin 35 of the driven shaft 29.

The axis of the bearing is perpendicular to the plane of the platform. The axes of the pivot pins 36 and 43 lie in a single plane and at right angles to each other, the point of intersection being in line with the axis of shaft 29, as indicated in Fig. 3. The platform 42 makes an acute angle 40 with the horizontal and is adapted to support a person, as stated supra. It may be provided with a corrugated rubber mat 47 on its upper surface to prevent slipping.

Secured to the rear leg portions 12 are upwardly 55

extending pipes or columns 48 connected at their upper ends by vertically spaced members 49 and 50 which serve as handles for a person standing on the platform 42. A switch 51 controls the motor 16 and is conveniently located, for example, on the cross member 50. Any suitable conventional electrical wiring, not shown in the drawings, may be used for energizing the motor 16.

The device operates as follows:

- 10 When the operator desires to use the health machine, particularly for body developing and exercising, such as developing the foot, leg and body muscles and joints, he steps upon the platform 42, takes hold of either one of the cross bars 49 or 50, to serve as a handle bar to maintain balance, if necessary, and turns on the switch 51 to start the motor 16. By means of the speed-reducing train of gears in box 14, the shaft 29 is rotated and its associated pin 35 revolves therewith.
- 15 20 As the pin 35 is inclined from the vertical and as the platform 42 is always perpendicular to the pin through enclosing it in the bearing 46, it is clear that the platform will always be tilted as the pin revolves.
- 25 The low point of the platform will move around the shaft 29 once with every turn of that shaft, as will the high point which will be spaced diametrically opposite the low.

As the shaft 29 rotates, the pin 35 imparts to the platform a double oscillating movement once about the axis defined by the pivot pins 43, and then simultaneously about the axis defined by the pivot pins 36 at right angles to the first mentioned axis.

35 The platform will, in effect, roll upon the surface of a cone having its apex in the platform and on the center line of the shaft 29 with its major axis vertical. This movement of the platform is made possible by the pivotal mountings disclosed which, in effect, constitute a gimbal joint, and by the fact that the point of intersection of shaft 29 and pin 35 lies in the same plane defined by the pivot pins 36 and 43.

40 As the upper surface of platform 42 extends, as is seen in Figs. 3 and 4, through the intersection of the center lines of the shaft 29 and the pin 35, it follows that the point in the platform coinciding with the intersection is substantially a dead point.

45 The platform 42 is of sufficient size, as before stated, to receive the two feet of the user, one upon each side of this dead point, and of a dividing line through this point. One foot of the user is shown in dotted lines in Fig. 3 with the user facing the handles 49 and 50.

50 With the user so positioned on the platform, it is obvious that, as the low point of the tilted platform moves around its periphery, that, depending upon the direction of rotation of shaft 29, first the heel will be below the sole and then above it; further, that first the inside of the foot will be higher than the outside, and then it will be lower; and still further, that first one foot will be higher than the other and then it will be lower. If the direction of rotation of the shaft 29 is reversed, then the sequence is the reverse of that indicated.

55 These movements imparted to the feet of the user thoroughly exercise the feet and ankles as well as the leg muscles. The change in the relationship between the feet exercises a large part of the body muscles, especially the legs and abdominal muscles. It further has an effect of kneading and massaging the internal organs, and consequently, is very beneficial to the system and the general health.

While the drawings show a preferred embodiment of the invention, numerous changes and alterations may be made without departing from the spirit of the invention.

I, therefore, do not limit myself to the details of construction and arrangement, as shown, but claim my invention as broadly as the state of the art permits.

I claim:

1. An exercising apparatus, including a base, 10 a plate mounted on said base for universal tilting motion, a crank shaft having an angularly disposed section rotatably seated in and normally supporting said plate in an inclined position, a motor, reduction gearing between said motor and 15 said shaft, and handle bars mounted on said base.

2. An exercising machine, including a base, a frame pivotally supported about a horizontal axis on said base, a platform mounted in said frame to form a gimbal joint therewith, and a shaft 20 maintaining said platform in inclined position and imparting rotary drive to said platform.

3. A machine of the character specified, including a base, a frame supported on said base for tilting in a vertical plane, a platform in said frame supported for tilting in a vertical plane at right angles to said first mentioned plane, and means 25 for actuating said frame and said platform.

4. In an exercising machine a support, an open-top frame pivotally secured thereto about a horizontal axis, a plate adapted to support the weight of a user secured to said frame for pivotal movement and positioned within the confines thereof, said plate being capable of pivotal movement about one axis on said frame and conjoint movement with said frame about an axis at right angles to said one axis, and means acting on said plate to affect universal tilting of 30 said plate.

5. In an exercising machine a support, a frame 40 pivotally secured thereto about a horizontal axis, a plate positioned within the limits of and secured to said frame for pivotal movement relative thereto about an axis at right angles to the pivotal axis of said frame, said plate and frame 45 being adapted for conjoint movement about the pivotal axis of said frame, and means acting on said plate to impart thereto a rolling tilting motion.

6. In combination with a support, a frame pivotally secured thereto about a horizontal axis, 50 a plate pivotally secured to said frame upon an axis lying substantially in its top surface to provide a gimbal joint, and means for maintaining said plate in sloping position and imparting thereto a universal tilting motion.

7. In an exercising machine a support, a gimbal joint carried by said support upon a horizontal axis, one part of said gimbal joint being formed as a platform to permit a person to stand thereon, means for imparting a rolling motion to said platform, and handle bars secured to said support adapted to be held by a person while occupying said platform.

8. In an exercising machine a support, a frame 55 mounted for pivotal movement about a horizontal axis on said support, a platform positioned in said frame and secured for pivotal movement relative thereto about an axis spaced angularly from said first-mentioned axis, in the same plane and adapted to receive the feet of and support the user, and means acting on said platform to effect a rolling tilting movement thereof in a plurality of planes.

9. An exercising apparatus, including a base, 75

an inclined plate positioned closely adjacent a supporting surface, means non-rotatably mounting said plate on said base for universal tilting comprising horizontal axes which are angularly displaced, said plate serving as a standing platform for a person, means for actuating said plate with a universal tilting movement to cause said plate to affect the person standing thereon, said means for actuating being spaced from said mounting means, and handle bars carried by said base above and forward of said plate and affording a hold to the person standing thereon.

10. In an exercising apparatus, a base, a person supporting plate mounted on said base by pivoted means at its periphery for preventing rotation and for universal tilting motion, a crank

shaft having an angularly disposed section rotatably seated in and normally inclining said plate at an angle to the horizontal, and means for imparting rotation to said shaft to cause said plate to tilt progressively and to cause the low point of said plate to move around its periphery. 5

11. In combination with a support, a frame pivotally secured thereto by a horizontal axis, a plate pivotally secured to said frame upon an axis lying substantially in its top surface to provide a gimbal joint, and means for maintaining said plate in sloping position and imparting thereto a universal tilting motion, the meeting edges of said frame and plate being arcuate and in snug contact relation. 10 15

LOUIS GREENBERG.
